CLAIM

The ornamental design for a fire pit accessory storage caddy as shown and described.

DESCRIPTION

FIG. 1 is a front upper perspective view of a first embodiment of a fire pit accessory storage caddy showing my new design.

FIG. 2 is a rear upper perspective view thereof.

FIG. 3 is a front elevation view thereof.

FIG. 4 is a rear elevation view thereof.

FIG. 5 is a top plan view thereof,

FIG. 6 is a bottom plan view thereof,

FIG. 7 is a left side elevation view thereof.

FIG. 8 is a right side elevation view thereof.

FIG. 9 is a front upper perspective view of a second embodiment of a fire pit accessory storage caddy showing my new design.

FIG. 10 is a rear upper perspective view thereof.

FIG. 11 is a front elevation view thereof.

FIG. 12 is a rear elevation view thereof.

FIG. 13 is a top plan view thereof.

FIG. 14 is a bottom plan view thereof.

FIG. 15 is a left side elevation view thereof; and,

FIG. 16 is a right side elevation view thereof.

The dashed lines shown in the drawings are for purposes of illustrating portions of the fire pit accessory storage caddy that form no part of the claimed design.
